UNITED STATES PATENT OFFICE.

ALBERTIS C. TAYLOR, OF WARREN, OHIO, ASSIGNOR TO THE TAYLOR WELDER COMPANY, OF WARREN, OHIO, A CORPORATION.

MACHINE FOR HEATING RIVETS, &c.

1,354,859.

Specification of Letters Patent.

Patented Oct. 5, 1920.

Application filed May 1, 1920. Serial No. 378,273.

To all whom it may concern:

Be it known that I, ALBERTIS C. TAYLOR, a citizen of the United States, residing at Warren, in the county of Trumbull and State 5 of Ohio, have invented certain new and useful Improvements in Machines for Heating Rivets, &c., of which the following is a specification.

This invention relates to a machine for 10 heating rivets, etc., and the object of the invention is to provide a machine adapted to hold a pair of rivets for a short interval of time in an electric heating circuit in which the rivets themselves form part of the circuit 15 and electrically in series therewith. The rivets are also held in an angular or inclined position where both are plainly visible and readily engaged and removed singly and successively when heated to the required 20 degree. The machine is relatively small, compact and portable; it will heat a pair of rivets in a few seconds; the rivets are heated internally and uniformly which gives an ideal upsetting condition; scale on the rivets 25 is reduced to a minimum, and there is no waste; no current is consumed when the full complement of rivets are not in place; the heating of the rivet is under perfect control; and the machine is exceptionally simple and 30 easy to operate.

In the drawing accompanying this application, Figure 1 is a side view of the machine showing a rivet in place as in heating operations. Fig. 2 is a front view of the machine. Fig. 3 is a plan view and section on line 3—3, Fig. 1. Fig. 4 is a rear view and end elevation on line 4—4, Fig. 1. Fig. 5 is a diagram of an electric circuit showing the secondary circuit of the transformer and 35 two rivets and a conducting bar of my machine connected in series, as in heating operations.

The machine comprises a skeleton frame made of separate strips of angle-iron united 45 together in a particular way so as to support a set of heating and clamping conductors for the rivets in an inclined plane, in plain view and reach of the operator. Thus, each side of the frame comprises a straight piece of 50 angle iron adapted to form a rear leg 2, and a bent piece of angle-iron provides a front leg 3 with a slanting extension 4 united at its upper end with the upper extremity of rear leg 3 by a plate 5 and rivets 6. The 55 lower extremities of legs 2 and 3 are united

by a cross piece 7 and also by a relatively long piece of angle-iron 8 which is riveted at its lower end to leg 2 and extends upwardly and forwardly at an angle of about 45 degrees to a point where it intersects bend 60 9 in front leg 3 and thence projects about ten inches upwardly and forwardly beyond this bend. Right-angled clips 10 and bolts 11 unite the inclined piece 8 to leg 3 and said piece functions as a brace for the frame and 65 a support for an asbestos guard 12, a pair of electrodes 13 and 14, and a pan 15. The sides of the frame are alike and the corresponding legs connected by tie rods 16 and 17 and straps 18, while an angle-iron 19 and 70 a wide yoke 20 connect the corresponding inclined braces 8. Two straddle irons 21 and 22 also unite the slanting portions 4 of legs 3, and parallel guides 23 are fixed to the elevated portions of the saddle pieces 21 75 and 22. A heavy block or bar 24 of copper having end enlargements 25 is supported to slide on guides 23 with the enlargements 25 situated directly opposite the electrodes or terminals 13 and 14 of the secondary band 80 27 of a transformer 28 which is bolted and clamped in an inclined position beneath and between the slanting portions 4 of legs 3 of the skeleton frame.

The transformer electrodes or terminals 85 are secured and seated in an immovable insulated position upon yoke piece 20 of the skeleton frame, and the bar 24 rests freely in a movable position on the slides 23 and is adapted to be shifted back and forth at 90 either end in respect to the electrodes to permit rivets R of varying length to be introduced and engaged and clamped in an inclined position between the enlargements 25 and the vertically-inclined face of the electrodes 95 substantially as shown in Figs. 1 and 2. Because bar 24 is mounted to slide in an inclined position it tends to move by gravity toward the electrodes and its own weight is sufficient to clamp and hold the rivets in 100 place; however I also utilize a pair of coil springs 29 to hold bar 24 in sliding engagement with guides 23 and these springs also tend to move the bar toward the electrodes through the medium of a pair of pivoted 105 treads 30 and their respective links 31 which connect with the end projections or bosses 32 of bar 24. These bosses have sockets for the bent extremities of links 31 and the said parts are held in free-playing rela- 110

tion by loops 33 affixed to the slanting portion 4 of legs 3 and through which loops the links 31 extend and have perfect freedom of movement.

- 5 Upon pressing either treadle 30 the corresponding end of the conductor bar slides in an arc on the guide pieces 23, the fulcrum or point of turning being at the head of one of the rivets where it engages the enlargement 25. The weight of the bar tends to maintain this contact with one rivet while it is being tilted for the purpose of introducing or removing a second rivet, and contact is also maintained by the spring 29 for 10 the treadle which is not being operated. When both rivets are removed bar 24 is prevented from moving downwardly beyond a predetermined point as fixed by an adjustable stop or rest consisting of a short 15 piece of angle-iron 34 secured transversely to the lower end of a slotted plate 35 which is mounted upon saddle pieces 21 and 22 and adapted to be secured in adjusted position thereon by a clamping screw 36. Stop 20 piece 34 is long enough to engage both enlargements 25 when a rivet is not being held by the conductor bar, and the rocking or tilting movement of bar 24 may still be effected when the rivets are absent; that is, 25 the fulcrum or pivotal point is then at the point of engagement of one enlargement 25 with the stop piece 34, while a fulcrum may also be said to be established at the point of union between the bent extremity of the 30 link 31 for the idle treadle.

The rivets are handled by tongs or other suitable gripping instruments, and when a rivet is accidentally released it will fall 40 upon the inclined asbestos table 12 and pass down between the spaced terminals of the transformer and out at the front side of the machine. An electric switch 38 is also mounted upon the front side of the skeleton frame between legs 3 wherewith to control 45 the electric heating current passing through the transformer. It should also be particularly noted that in order to heat rivets or other objects it is necessary to place the two rivets or objects in series in the electric circuit, and that the separate conducting bar 24 is also placed in series with these rivets or objects and becomes a part of the heating circuit, see Fig. 5.

The machine shown and described herein 55 as a rivet heater is not necessarily limited or confined in use to the heating of rivets only; it may also be used for heating metal bars for bulldozers and for heating any object which is to be forged or worked. Therefore, the term "rivet" wherever used in the description and claims should not be interpreted too literally.

What I claim is:

1. A machine for heating rivets, etc., com-

prising a transformer having a secondary 65 circuit with stationary terminals, and a movable conductor mounted opposite said terminals adapted to place a pair of rivets in series in said circuit.

2. A machine for heating rivets, etc., comprising a set of work heating and clamping elements mounted and adapted to operate in an inclined plane and with the work accessible and also inclined.

3. A machine for heating rivets, etc., comprising a transformer having separate stationary electrodes, a clamping conductor movably mounted opposite and adapted to hold a piece of work against each stationary electrode, and means adapted to shift said 80 conductor back and forth in respect to said electrodes.

4. A machine for heating rivets, etc., comprising a transformer having electrodes, a clamping conductor for the rivets movably 85 mounted opposite said electrodes, and an adjustable stop to limit the movement of said conductor toward said electrodes.

5. A machine for heating rivets, etc., comprising a transformer having stationary 90 electrodes, a conducting bar mounted to tilt opposite and adapted to clamp the work to be heated against each electrode, and means adapted to effect a tilting movement of said bar.

6. A machine for heating rivets, etc., comprising a transformer having secondary bands provided with terminals stationed in an inclined plane, and a current conducting member for holding and heating the rivets 100 movably situated opposite said terminals.

7. A machine for heating rivets, etc., comprising a transformer having seating terminals for the rivets, a current-conducting rivet holding member movably situated 105 opposite said terminals, and selective mechanisms adapted to tilt said member alternately at its opposite ends.

8. A machine for heating rivets, etc., comprising a transformer having terminals with 110 inclined rivet seating faces, a current-conducting rivet holding member movably situated opposite said inclined faces, and separate treadle mechanisms adapted to shift the opposite ends of said member alternatively. 115

9. A machine for heating rivets, etc., comprising a transformer having separate work-seating terminals, a movable current-conducting bar situated opposite said terminals adapted to hold a separate piece of work 120 against each terminal, separate treadle mechanisms adapted to force said member away from said terminals, and springs adapted to press said member toward said terminals.

10. A machine for heating rivets, etc., comprising a transformer having stationary secondary terminals, a current-conducting bar adapted to hold the work separately 125

against each terminal, a treadle and link adapted to tilt said bar, and a spring adapted to force said bar toward said terminal.

11. A machine for heating rivets, etc., comprising a transformer having stationary secondary terminals, guides opposite said terminals, a current-conducting and rivet-holding bar slidably mounted upon said guides, and treadle mechanisms adapted to slide said bar upon said guides.

12. A machine for heating rivets, etc., comprising a transformer having terminals with inclined work-seating faces, inclined guides opposite said inclined faces, a current-conducting and work-holding bar seated upon said guides, and means adapted to cant said bar in respect to said terminals.

13. A machine for heating rivets, etc., comprising a transformer having secondary bands provided with stationary terminals, inclined guides opposite said terminals, a current-conducting and work-holding bar slidably seated upon said guides, an adjustable stop adapted to limit the movement of said bar toward said terminals, and separate spring-pressed treadle and link connections adapted to tilt the opposite ends of said bar in respect to said terminals.

14. A machine for heating rivets, etc., comprising a skeleton frame, a transformer having secondary bands with separate terminals secured in a stationary and insulated position upon said frame, a separate current-conducting and work-holding bar slidably seated upon said frame opposite said terminals, and separate treadle connections adapted to shift the opposite ends of said bar alternatively in respect to said terminals.

15. A machine for heating rivets, etc., comprising a skeleton frame having separate transformer terminals secured in a fixed inclined position thereon, a current-conducting and work-holding bar movably seated in an inclined position upon said frame opposite said terminals, means adapted to limit the movement of said bar toward said terminals, and means adapted to shift said bar.

16. A machine for heating rivets, etc., comprising a skeleton frame having inclined brace members, a transformer supported upon said frame having secondary bands

provided with terminals secured in a fixed inclined position upon said brace members, a separate current-conducting and work-engaging bar having an inclined seat upon said frame opposite said terminals, and separate treadles connected with the opposite ends of said bar adapted to tilt the bar in respect to said terminals.

17. A machine for heating rivets, etc., comprising a skeleton frame having separate inclined seats, and a transformer and its secondary terminals and a current-conducting and rivet-holding bar placed in apposition upon said inclined seats and adapted to hold a pair of rivets in an inclined and accessible position during heating operations.

18. A machine for heating rivets, etc., comprising a frame, a transformer mounted in an inclined position upon said frame having secondary bands with terminals fixed in an insulated and inclined position, a guard plate fixed in an inclined position between said secondary bands, and a current-conducting and work-holding bar movably mounted opposite said terminals.

19. A machine for heating rivets, etc., comprising a skeleton frame, a transformer secured to said frame having a secondary band with seating terminals for the work fixed in an insulated position upon said frame, a pan above and a guard plate beneath said terminals, and a current-conducting and work-engaging bar slidably mounted upon said frame opposite one side of said terminals.

20. A machine for heating rivets, etc., comprising a skeleton frame having sides with slanting portions and inclined braces intersecting and extending beyond said portions, a transformer fixed upon said frame having its secondary terminals fixed to said inclined braces, a current-conducting and work-engaging bar slidably supported in a slanting position opposite said terminals, and a treadle at each side of said frame connected with the end of said bar.

Signed at Warren, in the county of Trumbull and State of Ohio, this 27 day of April, 1920.

ALBERTIS C. TAYLOR.
